UNITED STATES PATENT OFFICE.

FRED A. READ, OF LYNN, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-STITCHING MACHINE.

1,170,330.

Specification of Letters Patent.

Patented Feb. 1, 1916.

Application filed August 9, 1913. Serial No. 783,893.

To all whom it may concern:

Be it known that I, FRED A. READ, a citizen of the United States, residing at Lynn, in the county of Essex and State of Massachusetts, have invented certain new and useful Improvements in Buttonhole-Stitching Machines, of which the following is a specification, reference being had therein to the accompanying drawing.

10 This invention relates to buttonhole stitching machines and more particularly to the type of machine which is known as the "Reece" buttonhole machine, wherein a stitch frame carrying the stitch forming mechanism on the one hand and a work clamp or support on the other hand, are relatively movable so as to enable the stitching to be carried along the sides of the buttonhole and around its end or ends. Such stitch forming mechanism comprises usually an eye-pointed needle carrying the upper thread and, below and opposed thereto, the so-called "complemental stitch forming mechanism" or "under-sewing mechanism," 25 which carries and operates an under thread in coöperation with the needle carrying the upper thread.

Among the objects of the present invention are the improvement in the construction and operation of the under-sewing mechanism, and rendering the same more efficient, less complicated and more durable than heretofore.

Another object is to improve the mode of forming stitches on a machine of this type, and to afford a new type of buttonhole stitch.

Other and more specific objects will appear in the hereinafter following description.

For convenience the present improvements are illustrated as applied to a design of machine generally similar to that illustrated in Patent No. 695,039, granted March 11, 1902, upon the invention of W. W. Dixon.

In the accompanying drawings forming a part hereof, Figure 1 is a partial right-hand elevation of a buttonhole stitching machine of the character heretofore referred to, and embodying the present improvements. Fig. 2 is a right-hand view of the under-sewing mechanism with the circu-

larly shifting stock carrying the movable parts detached from the other parts in Fig. 55 1. Fig. 3 is a rear elevation of the parts shown in Fig. 2. Fig. 4 in left-hand elevation shows the details of the looper cam and fittings seen to the left of the throat support in Fig. 3. Fig. 5 on an enlarged scale shows 60 details of the looper actuating connections taken on the plane 5, 5, of Fig. 3. Fig. 6 is a front elevation of the machine of Fig. 1 with certain parts above the upper needle omitted. Fig. 7 is a plan view of the under-sewing mechanism and stock. Fig. 8 is a partial front elevation showing the relation of the needle and looper at a different stage of operation from that of Fig. 6. Fig. 9 is a plan view of the looper with its carrier. Fig. 10 is a plan view of the looper actuating cam detached. Fig. 11 is a front view of the lever for actuating the needle carrier. Fig. 12 is a front view of the link for actuating said lever. Fig. 13 is an enlarged section on the plane 13, 13, of Fig. 6, showing a universal connection in the needle actuating mechanism. Fig. 14 shows a stitch and buttonhole which may be produced by the mechanism described, the same 80 having no visible purl or line of interlocking loops. Fig. 15 diagrammatically shows the nature of such stitch.

Certain parts are shown similar to, and may be as indicated in said prior Patent No. 695,039, requiring, therefore, no detailed or other description, excepting as follows: The machine includes the clamp frame 21, the casting 22 containing the needle bar 23, it carrying an eye-pointed needle 24 for manipulating the upper thread α , said needle bar and its casing being in practice mounted in the stitch frame 25 already referred to, the curb or cam casing 26 in practice secured to the movable stitch frame so as to travel with it 95 under the clamp frame, said casing 26 having suitable adjustable headed bolts 27 which bear against smooth ways 28 at the under side of the clamp frame, the rod 29 deriving its motion from a cam in the stitch 100 frame, the cutter 30 and its carrying lever 31, the under thread needle 32, the needle carrier 33 to which it is attached, said carrier being fitted to slide in a groove cut in the extension 34 forming a race and rising 105 from and preferably made as part of the

stock 35, said stock having the circular upper end 36 adapting it to receive at suitable times a circular movement, the gear 37 fast on a sleeve 38, extending from stock 35, the tension device 39 for the under thread and the throat plate 40; also the circular ring-like portion 41 of the casing 26, which receives within it the circular upper end 36 of the stock 35, and depending from said ring 41 a loop 42 having formed through it centrally at its lower end an opening of such size as to loosely receive hollow hub 43 of gear 37, the gear being applied to the sleeve 38 and fixed there by a suitable nut 44.

15. The sleeve 38 has extended through it the actuator 45 in the form of a hollow rod, said rod receiving through the opening in its lower end the second or underneath thread *y*, such thread being passed upwardly through the rod 45 and into the under thread carrier 32. The thread may pass out of the hollow rod 45 through an aperture at 46, passing about the tension device 39 before passing to the under thread needle 32.

20. The rod 45 has fixed to it below the gear 37 a ball or enlargement 47, it being as herein shown embraced between two loose cup-shaped disks 48 and 49, both loosely surrounding the rod 45 and contacting the ball 47, said disks being borne respectively upon the two forks 50, 51 of a lever 52 pivoted at 53 between two depending curved hangers 54, 54, these hangers being connected in a suitable manner as by screws 55, with 25 the loop-shaped depending portion 42 above referred to. The lever 52 is connected with the rod 29 as shown so that the cam operated movement of the rod causes the oscillation of the lever 52 and thereby reciprocates upwardly and downwardly the hollow rod or bar 45.

In continuing the description of the machine illustrated in the drawings hereof, reference will be made to the new parts involved in this invention, and to new arrangements and combinations of parts, during which reference will necessarily be made to parts which *per se* are not new herein, but are for the first time employed in the novel relations and arrangements sought to be covered herein.

The oscillatory member on which the under mechanism is seated may take any physical form, and will be termed a "stock," as 55 it is merely a carriage or frame for supporting the various working parts of the under mechanism. It shifts bodily, for example circularly, with all the working parts supported by it, and these parts themselves 60 move as may be required for stitching more or less independently of the stock's shifting.

The preferred needle operation may now be conveniently described in a general way. The upper needle 24 is one which penetrates 65 the work near the margin. The under

needle 32 is in the nature of a looper, not piercing the work, but passing from beneath to above, for causing the upper and under threads to interlock. Herein the terms "upper" and "under" are used only relatively, 70 and by "upper needle" will be understood any penetrating needle, and by "under needle" any loop forming needle opposed to such upper needle. The plane of movement of the under needle may be inclined 75 as indicated in Fig. 2, passing to one side of the vertical upper needle above the work and to the other side below the work. The needle operation is that the under needle during each ascent passes through a loop 80 of upper thread below the work, while above the work the under needle furnishes a loop of under thread which may be entered on the descent of the upper needle. The upper and under threads are thereby interlocked 85 both above and below the work. At each interlocking point the engaging bights or loops of the two threads form what may be termed a "lock." In successive stitches the locks will be in alignment forming what may 90 be termed the "lock line." Heretofore one or both of these lock lines have been located at the edge of the work, giving the effect of a purl.

Referring to Fig. 1, the upper thread *x* is 95 seen passing first to an upper tension 61, and thence to the eye of a lever or takeup 62, and thence to the upper end of the hollow needle bar 23, issuing from the lower end of the same and engaging the tension 100 63, from whence the thread passes to the eye of needle 24.

The under thread *y*, see Fig. 6, passing first upwardly through the hollow actuator 45, emerges at 46 engaging the tension 39, and passing thence to a guide 66, and thence to the movable upper end of the takeup lever 67, thence to an eye 68 on the needle carrier 33, and finally to the lower and upper eyes of the under needle 32. Coöperating 110 with these parts in the manipulation of the under thread, is the looper 71.

While it is possible with the machine hereof to produce the ordinary buttonhole stitch such as that of the prior Patent No. 695,039, 115 the novel stitch and buttonhole hereof may also be produced; see Figs. 14 and 15. Novelty is claimed not only in the machine hereof, but in the overseam or buttonhole stitching illustrated, the latter, however, being 120 made the subject of claim in copending application Serial No. 793,797, filed October 7th, 1913. Partly by reason of the novel constructions illustrated and described, and partly by readjustment of the tensions and other thread manipulating parts, it is found that the advantageous stitch illustrated may be produced. The characteristic feature of the illustrated stitch is the elimination of the purl effect by the practical concealment 125 130

of the interlocking thread loops. This is accomplished by so manipulating the upper and under threads that the upper and under lines of locks coincide with the line of penetration of the upper needle.

Fig. 15 illustrates the principle of the new stitch, which may be said to consist of an overseam comprising an upper thread *x* penetrating the work at a series of points 5 near the margin, thereby forming a series of bights located at, or even slightly within the under surface of the work, together with an under thread *y* which is formed into a series of loops, each loop having both strands 10 passing through one of the said bights of the upper thread, thence forming bends 72 extending around both faces and the edge of the work, and finally forming a bight of under thread which encompasses both 15 strands of upper thread at their point of penetration of the work. Thereby the line of locks 73, 73, etc., at the upper side of the work, and the line of locks 74, 74, etc., at the under side of the work, practically coincide 20 with the line of penetration, thus any visible purl effect is practically eliminated, and a substantial, durable and attractive buttonhole is afforded, consisting apparently merely of a series of adjacent loops of under 25 thread.

The usual work clamp above the clamp plate 30 is, of course, to be assumed, and relative movements between the work and the stitching mechanism may be secured in any desired manner for the purpose of causing the 35 line of stitches to advance along the sides, and if desired, circularly around the ends of the buttonhole. The lengthwise movement may, for example, be attained by the bodily 40 shifting of the stitch frame 25 with which moves the entire stitching mechanism. The relative movement around the ends of the buttonhole may be effected by rotation of the stitch mechanism relatively to the work. 45 Thus the stock 36 carrying the under sewing mechanism and the needle bar 23 carrying the upper needle may be revolved in unison. A gear 82 connected to the upper needle bar is rotated by a toothed segment 83; likewise 50 the gear 37 of the under mechanism is rotated by a segment 84. This is a usual construction, and it is sufficient to merely indicate the parts 85, 85, etc., by which the segment 84 is caused to swing in unison with 55 segment 83.

We come now to the details of the under mechanism. As explained, the intermittent shifting of the under mechanism is effected by a segment and gear. The operations, 60 however, of the movable parts carried on the stock 35 are all shown as effected from the single up and down moving actuator 45, connections from which extend to the looper, to the under needle and to the take-up for actuation thereof.

The connections between actuator 45, and needle carrier 33 are shown as follows: A short link 87 is at its lower end connected directly to the actuator 45, and at its upper end to an intermediate portion of a bent lever 88, which latter is pivoted at 89. The lever is formed with an aperture at 89^x surrounding the stud which connects link 87 to actuator 45, permitting relative play between them. The lever 88 is extended upwardly 70 to where at its upper end a ball and socket pivot 90 (see Fig. 13) affords a connection between the lever and a link 91, which link at its opposite end has a similar ball and socket pivot 92 connecting it directly to the 75 front of the needle carrier 33. Adjustment between lever 88 and link 91 is permitted by a lengthwise slot shown at 93, Fig. 11, in which engages the screw secured block 94, Fig. 13. By unscrewing, the pivot 90 can 80 be raised or lowered, thus increasing or decreasing the throw of link 91 and the needle carrier. Obviously, the up and down movement of the actuator 45 causes the upper end of lever 88 to swing about the pivot 89, 90 thereby pulling and pushing link 91 in a generally lateral direction, its movements being communicated to the needle carrier and under needle; thus there are only three moving parts between actuator and carrier. 95

The takeup 67 is shown as a three-armed lever having a short leftwise spring actuated arm 97, tending to hold the takeup's main arm 67 in contact with a stud and roller 98 on the lever 88. The takeup thus 100 oscillates with the swinging of the lever, and without the interposition of any additional parts between the takeup and the actuator. As usual, an adjustable stop 99 for the heel 105 of the takeup may be employed to regulate the extent of the takeup movement. The looper and its actuation are likewise simplified so that the necessary compound movement is secured with minimum parts and maximum efficiency. The looper has 110 two motions, first a bodily to and fro swinging toward and from the under needle, and second, a slight oscillation in a direction lateral to the to and fro swinging, resulting in a curved path. The well understood purpose of this motion is that the looper which is barbed may advance through the loop carried by the upper needle, and thence pass to and slightly around the path of the under needle, so that the looper may deliver the 115 loop to the under needle and then retract. Usually the looper has been in the form of a barbed hook swiveled to its carrier and actuated by separate trains of mechanism, one for swinging, the other for oscillating the 120 looper, with proper timing to give the desired resultant path. Herein the mechanism is so simplified that four moving parts between the actuator and looper suffice. A link 101 adjustable lengthwise by screw de- 125 130

vice 102 extends from the actuator below to its connection to a bell crank lever 103 above, by a radially adjustable pivot 104, see Fig. 5. The bell crank lever serves to convert the vertical to a horizontal motion, which is communicated by a link 105 to a looper carriage 106. This carriage slides upon a slight incline from the horizontal, being held and guided by a fixed guide member 107 formed with overlying flanges. The sliding carriage 106 to which the link 105 is pivoted, has a front portion 108 fixed to it in an adjustable manner, so that by loosening the screws 109, 110, the position of the looper relatively to the carriage may be altered. The member 108, by means of a pivot 111, has the looper carrier 112 mounted at its upper side.

Referring to the top views, Figs. 7 and 9, it will be seen that the looper is no longer the reversely hooked or curved member already known, but is a short straight member which, when retracted, is located in a position withdrawn from the path of the upper needle. The looper carrier 112 is shown L-shaped so as to afford an offset between the looper and its line of movement on the one hand, and the looper carriage and its connections to the carrier on the other hand.

In consequence, it is possible to entirely dissociate the needle and takeup actuating mechanism which are at the front, Fig. 6, and the looper mechanism which is wholly at the rear side of the stock, see Fig. 3.

The connections for longitudinally reciprocating the looper have been described. Its slight transverse reciprocation is effected about the pivot 111 by means of a self-acting device requiring no connection from the actuator. This device preferably consists of a relatively fixed cam 114, see Figs. 7 and 10, which may be generally straight but with a deflecting portion or lug 115, which acting upon the pin or cam follower 116 causes the looper, near the end of its advance movement, to slightly swing reversely transversely, thus carrying the barb of the looper about the path of the under needle. The cam 114 is shown as having only one active face, and consequently a spring 117 is employed to hold the pin 116 into contact with the cam. The spring is held compressed between the carrier 112 and a small bracket 118, which, for convenience, is held in place by screw 119. The outer end of the contact pin 116 is shown as screw threaded and engaged by a lock nut 119, thus affording a device for adjusting the pin, and thereby the relation between the carrier and the cam.

The cam 114 is shown as a thin plate, and this is rendered longitudinally adjustable by reason of the elongated slot 120 engaged by the securing screw 121. The longitudinal adjustment of the cam determines the point at which the slight transverse throw of the

looper occurs, so that it can be accurately adjusted to the under needle's path.

It will be noticed that, simple though the described mechanism is in the small number of its parts, it nevertheless is extremely flexible in its capability of adjustment to meet all conditions. Thus the mechanism can be adjusted as to the time of operation of several parts, needle, takeup, looper, etc., and as to the speed of movement, and in some cases the acceleration as well as the actual distance covered; and the looper's path of movement is enabled to be altered as described. It will thus be seen that there has been described a stitching machine, attaining the objects and advantages before recited, and other advantages will be apparent to those skilled in the art.

Since many matters of design, arrangement, detail and other features may be indefinitely altered without departing from the novel principles disclosed, there is no intention to restrict the present invention to any features excepting as specified in the claims appended hereto.

What is claimed and desired to secure by Letters Patent is:

1. In a buttonhole stitching machine the combination of an upper needle having means for reciprocating it, and an under sewing mechanism comprising a shiftable stock, a movable actuator shiftable with the stock, and the following carried by the stock: an under needle carrier, a swinging lever pivoted near its lower end and swung by the actuator, a link between the lever's upper end and the carrier, and a device for effecting up-and-down adjustment of the connection between said link and lever to vary the needle travel.

2. In a buttonhole stitching machine the combination of an upper needle having means for reciprocating it, and an under sewing mechanism comprising a shiftable stock, a movable actuator shiftable with the stock, and the following carried by the stock: an under needle carrier, a swinging lever pivoted near its lower end and swung by the actuator, a link between the lever's upper end and the carrier, and a device for adjusting the effective length of the upwardly extending portion of said lever to vary the needle travel.

3. In a buttonhole stitching machine the combination of an upper needle having means for reciprocating it, and an under sewing mechanism comprising a shiftable stock, a movable actuator shiftable with the stock, and the following carried by the stock: an under needle carrier, a swinging lever pivoted near its lower end and swung by the actuator, a link between the lever's upper end and the carrier, the lever shaped with a recessed portion adjacent the actuator, a stud located loosely in such recess af-

fording a pivot for a link, and said last named link, the same connecting the actuator and lever.

4. In a buttonhole stitching machine the combination of an upper needle having means for reciprocating it, and an under sewing mechanism comprising a shiftable stock, a movable actuator, and the following carried by the stock: an under needle carrier, connections from the actuator for reciprocating said needle carrier, a looper and carrier, a carriage for said looper carrier for guiding it toward and from the needle path, a lever arm pivoted on the stock, an up-and-down moving link directly from said actuator to said lever arm and a side moving link directly between said lever arm and said carriage.

5. In a buttonhole stitching machine the combination of an upper needle having means for reciprocating it, and an under sewing mechanism comprising a shiftable stock, a movable actuator, and the following carried by the stock: an under needle carrier, connections from the actuator for reciprocating said needle carrier, a looper and carrier, a longitudinally sliding guide-carriage, means mounting said looper carrier on said guide-carriage to have lateral movement relatively thereto, connections from the actuator for sliding the carriage to advance and retract the looper carrier, and a device for causing displacement of the looper carrier laterally with respect to and during carriage movement consisting of a cam and follower device one part of which is relatively fixed on the stock, the other movable with the looper carrier, whereby the looper carrier's advance or retraction brings about its lateral displacement.

and a device for causing displacement of the looper carrier laterally with respect to and during carriage movement.

6. In a buttonhole stitching machine the combination of an upper needle having means for reciprocating it, and an under sewing mechanism comprising a shiftable stock, a movable actuator, and the following carried by the stock: an under needle carrier, connections from the actuator for reciprocating said needle carrier, a looper and carrier, a longitudinally sliding guide-carriage, means mounting said looper carrier on said guide-carriage to have lateral movement relatively thereto, connections from the actuator for sliding the carriage to advance and retract the looper carrier, and a device for causing displacement of the looper carrier laterally with respect to and during carriage movement consisting of a cam and follower device one part of which is relatively fixed on the stock, the other movable with the looper carrier, whereby the looper carrier's advance or retraction brings about its lateral displacement.

In testimony whereof I affix my signature in presence of two witnesses.
